(57) **CLAIM**

The ornamental design for a coating film transfer tool, as shown and described.

DESCRIPTION

FIG. 1 is a perspective view of a coating film transfer tool, showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a cross-sectional view thereof taken along lines 8-8 shown in FIG. 2;

FIG. 9 is a front view thereof in an alternate configuration; and,

FIG. 10 is a front view thereof in an open configuration.
